UNITED STATES PATENT OFFICE.

IRWIN EMANUEL STEINBERGER, OF NEW YORK, N. Y.

DESIGN FOR A GLOVE.

Application filed February 5, 1927. Serial No. 20,634. Term of patent 3½ years.

To all whom it may concern:

Be it known that I, IRWIN E. STEINBERGER, a citizen of the United States, and a resident of the city of New York, borough of Manhattan, in the county and State of New York, have invented a new, original, and ornamental Design for Glove, of which the following is a specification, reference being had to the accompanying drawing, forming part thereof.

In the drawing A are diamond-shaped figures of a different color from that of the cuff, and a are cord-like connections between the figures of the same color as said figures.

I claim:

The ornamental design for a glove, substantially as shown and described.

IRWIN EMANUEL STEINBERGER.
